(57) **CLAIM**

The ornamental design for a chili pepper shaped carabiner, as shown and described.

DESCRIPTION

FIG. 1 is a top plan view of my new design for a chili pepper shaped carabiner, it being understood that the bottom view is a mirror image thereof;

FIG. 2 is a left side elevational view of the chili pepper shaped carabiner shown in FIG. 1;

FIG. 3 is a right side elevational view of the chili pepper shaped carabiner shown in FIG. 1;

FIG. 4 is a front elevational view of the chili pepper shaped carabiner shown in FIG. 1;

FIG. 5 is a rear elevational view of the chili pepper shaped carabiner shown in FIG. 1; and,

FIG. 6 is a top perspective view of the chili pepper shaped carabiner shown in FIG. 1.
